FOLDING SHEET MATERIAL

Thomas C. Rowen, Swampscott, Mass., assignor to
 United Shoe Machinery Corporation, Paterson,
 N. J., a corporation of New Jersey

Application April 27, 1932, Serial No. 607,767

13 Claims. (Cl. 12—55)

This invention relates to a method of folding the margin of a piece of sheet material by the use of a cement which is normally not tacky but may be rendered tacky by the application of a suitable agent and to a folding machine equipped to handle work which has a coat of this sort of cement.

In the manufacture of the uppers of boots and shoes it is customary to fold certain margins of the shoe parts in order to produce smoothly finished edges thereon. Two procedures are in common use. In the first the margin of the shoe part is skived, a coating of cement is applied to the margin, and then the margin is folded over upon the body portion. In the second a narrow binding strip—usually of fabric—is sewed along an edge of the shoe part, said strip being provided, either before or after its attachment, with a coat of cement, and then the free portion of the binding is folded over upon the sheet material. Thus in both cases the cement coated margin of a piece of work is folded over upon the body portion thereof. It has been proposed to use a cement which is normally non-sticky but is adapted to become sticky upon being treated with a suitable softening agent, for example heat; and the present invention relates to the folding of sheet material with the use of a cement of this kind which is normally non-sticky.

It is desirable to strengthen the work at or adjacent to its folded edge by the application of a strengthening member such as a piece of tape; and in one aspect the invention comprises a method in which there is directed upon the body portion of a piece of work having a coating of thermoplastic cement upon a margin thereof, a piece of tape having a similar coating, progressively softening the two coatings and progressively pressing the tape upon the work and folding the margin of the work. As herein illustrated, the tape is pressed upon the body portion of the work close to the cemented margin thereof, the softening is accomplished by a blast of hot gas, and the margin is folded over upon the tape.

Hitherto mechanisms embodied in folding machines for producing hot gas and directing it upon the work have comprised an electric heat unit provided with a rheostat for varying its temperature, a blower or fan, and a conduit leading from the blower past the heat unit to a nozzle. Such a blower produces a constant current of air at almost negligible pressure; and consequently a heat unit of considerable capacity must be used. There is thus a comparatively slow

moving, very hot current of air directed toward the work and a very hot heat unit; and the only way in which the amount of heat delivered to the work can be increased is to increase the heat of the unit by manipulating the rheostat. The high temperature of the heat unit results in excessive radiation of heat which is annoying to the operator; and the satisfactory control of the comparatively high temperature of the slowly moving current of air at the nozzle is difficult. Moreover, because of the fact that the nozzle must be pointed down upon the work and the movement of the current of air is comparatively slow, the hot air is more or less dissipated instead of being all carried to the work. In order to obviate these disadvantages there is provided, in combination with work-feeding and folding instrumentalities, a nozzle, a constant source of heat, a positively acting pump for forcing gas under substantial pressure past the source of heat through the nozzle, and means for varying the pressure. In the illustrated machine the source of heat is an electric heat unit through a spiral passage around which the air is forced, and the positively acting pump is one capable of producing a pressure of several pounds per square inch. With this construction in which a considerable pressure is used, the amount of heat delivered to the work may be very delicately controlled by manipulating the relief valve to increase or decrease the pressure of the air, and practically all of the fast moving air delivered from the nozzle reaches the work.

Referring now to the accompanying drawings,

Fig. 1 is an elevation of a machine by the use of which the method may be conveniently practiced, a piece of work being shown in process of being operated upon;

Fig. 2 is a detail principally in section of the heating means;

Fig. 3 is a chart showing the amounts of heat delivered at certain specified pressures; and

Fig. 4 is a section on an enlarged scale showing a finished piece of work comprising a piece of leather having a piece of tape along one edge thereof and a strip of binding folded about the edge of the leather and over upon the tape.

Referring first to Fig. 1 the folding machine comprises a base 5 adapted to rest upon a bench and an arm 7 having at its outer end a work support 9 over which the work is fed. The particular work shown is part of the strap of a ladies' pump and comprises a piece of leather 100 having attached to its margin a strip of fabric binding 200. On the left hand side of the work a piece of

tape 300 has been applied to the leather or body portion of the work, and the binding has been folded over and pressed down upon the tape. On the right-hand side of the work, the tape 300 is being directed upon the leather, and the binding 200 is in process of being folded.

As herein illustrated the tape 300 has a coating of thermoplastic cement on that face which, in the finished work, contacts with the leather; and the binding 200 has a similar coat on that face which, in the finished work, contacts with the tape. A presser or creaser 11 engages the edge of the leather and has a slot inclined downwardly in the direction of feed movement of the work through which the tape passes as it is directed upon the margin of the leather. A slender guide 13 engages the edge of the leather, a folding finger, not shown, bends the binding about the edge of the leather, and a hammer 17, having a four-motion feed movement, presses the binding against the tape and the tape against the leather and also acts to feed the work intermittently away from the observer as viewed in Fig. 1. The tape 300 is fed in a suitable manner from a reel, not shown, through a guide slot in a small bar 19, and from there is directed upon the work and fed with the work by the hammer which, stated above, has a four-motion movement. The small bar 19 has a hole in its inner end to receive a threaded 30 stud 28 carried by the frame of the machine and is held adjustably in position by a clamp nut 22.

The folding machine, except for the tape guide, the edge guide 13 and certain changes in the shape of some of the work engaging parts is or 35 may be substantially the same as that shown in United States Letters Patent No. 1,702,598, granted February 19, 1929 upon an application filed in the name of Perley R. Glass and no further description of it will be given since the 40 details of its construction form no part of the present invention and any suitable folding machine may be used. It will be understood, however, that the work, including the tape, is fed intermittently away from the observer, as viewed in Fig. 1, that the tape is progressively directed upon the leather or body portion of the work, and that the binding or margin of the work is progressively 45 folded over and pressed upon the tape.

The tape and the binding each carry a coat of 50 thermoplastic cement, the tape being coated on that face which will contact with the work, and the binding being coated on that side which will contact with the upper uncoated face of the tape as it lies upon the work. In order to soften these 55 coatings progressively there is provided a nozzle 21 so located as to direct a blast of hot air upon the coated side of the tape and the coated side of the binding simultaneously. This blast strikes the tape just before it enters the guiding groove 60 in the presser foot 11 and strikes the binding just before it passes this foot. This nozzle is fast to the lower end of a curved pipe 23, the upper end of which (Fig. 2) is fast to a nipple 25 which leads from a straight passageway 27 in a member 28 provided with a hand wheel 29 and rotatably mounted in a sleeve 31, there being a 65 conical, gas-tight, ground joint between these two members which are held from longitudinal movement with respect to each other by a compression spring 33 seated on the end of the sleeve 31 and engaging a nut 35 threaded on the small 70 end of the member 28. By manipulating this hand wheel, the nozzle may be swung up into inoperative position at any time. The passageway 75 27 communicates with one end of a spiral pas-

sageway 37 in a cylindrical casing 39 mounted on the frame of the machine and having an electric heat unit 41 located within the coils of the spiral passageway. A pipe 43 connects the passageway 37 with the outlet of a positively acting air pump 45. This pump may be of any suitable type which is capable of producing a considerable pressure of air, the illustrated pump being a rotary one driven from any suitable source of power by a belt, not shown, which may be placed upon any one of the three pulleys 49 on the driving shaft 51. In order to permit the pressure to be varied while the pump is running, a pipe 53 connected at its lower end to the outlet pipe 43, has its upper end closed by a relief valve 55 held down by a compression spring 57 the tension of which may be varied by turning an adjusting nut 59.

The possibilities of an apparatus of this type appear in the chart shown in Fig. 3, which shows graphically the results obtained by the use of a 20 heat unit of 150 watts and pressures from about two ounces to four pounds. The curve of the graph would, of course, vary somewhat in accordance with the construction of the apparatus and the nature of the materials used but the 25 graph shows in general what occurs. The vertical column of figures represents thermal units, that is the temperature of the air just outside the nozzle, multiplied by the volume of air passing through the nozzle per second. The horizontal 30 line of figures represents the pressure of air at the nozzle in pounds per square inch. It will be noted that the thermal units delivered by the nozzle increase very rapidly with increase in pressure up to one-half pound pressure and continue to increase although less rapidly up to four pounds pressure. With the particular apparatus from which this chart was made and with a piece of work coated with a commonly used commercial thermoplastic cement, a pressure of one 40 pound was found to result in a proper softening of the cement.

The hot air delivered to the work has a tendency to heat undesirably adjacent portions of the machine; and in order to withdraw some of 45 this hot air from the locality adjacent to the work, a suction pipe 61 which leads to the inlet of the pump has its intake opening 63 located to withdraw hot air which may collect in the neighborhood of the work-engaging parts of the 50 machine. This withdrawal of hot air not only prevents undesirable heating of the work-engaging parts of the machine, but carries back to the pump air which is already somewhat warm and will require less expenditure of heat to raise it 55 again to the desired temperature.

Although the tape has been shown and described as being directed into such a position on the work that the margin of the work is folded over upon it, it should be understood that 60 the invention is not limited to this particular location of the tape, and although the illustrated machine has been described as directing a blast of hot air upon a coated tape as well as upon the margin of the work it should be understood 65 that the machine is effective to heat the cement on the margin and to fold said margin whether or not a piece of tape is used.

Having thus described the invention, what I claim as new and desire to secure by Letters 70 Patent of the United States is:

1. The method of folding a piece of sheet material having upon a margin thereof a coat of thermoplastic cement and at the same time strengthening said material which comprises 75

progressively directing upon the body portion of the sheet material a separate piece of tape having on that side which will be in contact with the sheet material a coat of thermoplastic cement, progressively heating the two coats of cement simultaneously while the tape and the margin are in separated relation, and thereafter progressively pressing the tape against the sheet material and folding the margin.

10 2. The method of folding a piece of sheet material having upon a margin thereof a coat of thermoplastic cement and at the same time strengthening said material which comprises progressively directing upon the body portion of the sheet material a separate piece of tape having on that side which will be in contact with the sheet material a coat of thermoplastic cement, progressively directing a blast of hot gas upon the two coats of cement simultaneously while the tape and the margin are in separated relation, and thereafter progressively pressing the tape against the sheet material and folding the margin.

15 3. The method of folding a piece of sheet material having upon a margin thereof a coat of thermoplastic cement which comprises progressively directing upon the body portion of the sheet material a separate piece of tape having on that side which will be in contact with the sheet material a coat of thermoplastic cement, thereafter progressively folding the margin over upon the tape, and progressively heating the two coats of cement prior to the folding operation.

20 4. The method of folding a piece of sheet material having upon a margin thereof a coat of thermoplastic cement which comprises progressively directing upon the body portion of the sheet material a separate piece of tape having on that side which will be in contact with the sheet material a coat of thermoplastic cement, thereafter progressively folding the margin over upon the tape, and directing a blast of hot gas upon the two coats of cement to soften them prior to the folding operation.

25 5. The method of folding a piece of work which comprises a piece of sheet material to which a strip of binding coated with thermoplastic cement is attached which comprises progressively directing upon the margin of the sheet material a piece of tape coated with thermoplastic cement on the side which is to contact with the piece of sheet material, progressively heating the cement on the binding and on the tape, and progressively folding the binding over upon the tape.

30 55 6. The method of folding a piece of work which comprises a piece of sheet material to which a strip of binding coated with thermoplastic cement is attached which comprises progressively directing upon the margin of the sheet material a piece of tape coated with thermoplastic cement on the side which is to contact with the piece of sheet material, progressively directing a blast of hot gas upon the cement on the binding and on the tape, and progressively folding the binding over upon the tape.

35 7. A machine of the class described having, in combination, a support over which a piece of work is fed, means for folding the margin thereof, means for directing upon the work prior to the folding operation a piece of tape having a coating of hard thermoplastic cement thereon, and means for directing upon the tape before it

reaches the work a blast of hot air to soften the cement.

8. A machine of the class described having, in combination, a support over which a piece of work having a coating of thermoplastic cement on the margin thereof is fed, means for folding the marginal portion of the work over upon the body portion and for pressing the folded-over margin against the body portion, means for directing a blast of hot gas upon the work prior to the completion of the fold to cause the cement to be softened, and means for withdrawing heated gas from the locality in which it is delivered by the nozzle to avoid undesirable heating of the work engaging parts of the machine.

15 9. A machine of the class described having, in combination, a support for a piece of sheet material having upon a margin thereof a coat of thermoplastic cement, means for feeding the sheet material over the support, means for directing upon the body portion of the sheet material a piece of tape having a coating of thermoplastic cement on one side thereof, means for softening the coats of cement on the tape and on the margin of the material, and means for pressing the tape against the body of the sheet material and for folding the margin of said material.

20 10. A machine of the class described having, in combination, a support for a piece of sheet material having upon a margin thereof a coat of thermoplastic cement, means for feeding the sheet material over the support, means for directing upon the body portion of the sheet material a piece of tape having a coating of thermoplastic cement on one side thereof, means for softening the coats of cement on the tape and on the margin of the material, and means for folding the margin over upon the tape.

25 11. A machine of the class described having, in combination, a support for a piece of sheet material having upon a margin thereof a coat of thermoplastic cement, means for feeding the material over the support, means for directing upon the sheet material a piece of tape having a coating of thermoplastic cement on one side thereof, means for directing upon the two coats a blast of hot gas to soften them, and means for pressing the tape against the body portion of the sheet material and for folding the margin.

30 12. A machine of the class described having, in combination, a support for a piece of sheet material having upon a margin thereof a coat of thermoplastic cement, means for feeding the material over the support, means for directing upon the sheet material a piece of tape having a coating of thermoplastic cement on one side thereof, means for directing upon the two coats a blast of hot gas to soften them, and means for folding the margin over upon the tape.

35 13. A machine of the class described having, in combination, a support over which a piece of work is fed, means for folding the margin of the work, means for directing upon the work along a path substantially parallel with the edge of the work to underlie the folded margin thereof and prior to the folding operation a piece of tape having a coating of hard thermoplastic cement thereon, and means for heating and softening the cement prior to the completion of the folding operation.

70 THOMAS C. ROWEN.
